ELECTROLIFT

Carl E. Johnson, Pasadena, Calif.

Application April 9, 1932, Serial No. 604,257

18 Claims. (CL 60—52)

My invention relates to thrust-exerting devices, and more particularly to a novel structural combination in which an electric motor or other rotary drive means is effective in producing a reciprocating movement of a piston through hydraulic means.

The invention finds particular utility in installations wherein it is desirable to be able to build up rather large thrust forces with a minimum of current consumption, and it is a primary object of the invention to combine in a single structure a hydraulically actuated piston, an impeller or other pump means for supplying liquid under pressure to this piston, and a drive means for the pump.

Further objects of the invention lie in the provision of a structure wherein the motor or other drive means is enclosed by the same shell which encloses the remainder of the parts, and in which the motor or other drive means can itself be surrounded by the operating liquid.

Further objects lie in a novel cooling system for the motor.

Other objects and advantages of the invention lie in the provision of a novel assembly which can be readily adapted to different installations and in which the elements are mounted in a novel manner.

Still further objects lie in the positioning of the pump means in spaced relationship with the piston, and in the novel shock-absorbing system acting between the piston and the shell.

The invention also includes a novel protector for the junction of the reciprocating rod and the shell.

Still other objects and advantages of the invention will be apparent to those skilled in the art from the following detailed disclosure of the preferred form of the invention.

Referring to the drawing,—

Fig. 1 is a vertical sectional view of the assembled structure.

Figs. 2 and 3 are horizontal sectional views taken on the corresponding lines of Fig. 1.

The invention will be shown and described in conjunction with an electric motor, but it should be understood that other types of drive means may be utilized.

Referring particularly to Fig. 1, the invention includes an outer shell 10 of cylindrical form and closed at its upper and lower ends by heads 11 and 12 which are preferably removable with respect to the outer shell and cooperate therewith providing an enclosing structure. These heads are held in clamping relationship with

the ends of the outer shell 10 by rods 13 which extend therebetween, the lower ends of these rods being suitably secured to the lower head 12 and the upper ends thereof extending through the upper head 11 so as to receive nuts 14.

A spacer sleeve 18 surrounds each of the rods 13 and cooperates with a spacer 19 in positioning a wall 20 with respect to the outer shell 10, this wall being hereinafter termed an auxiliary wall. As best shown in Fig. 3, this wall includes lugs 21 extending outward from its periphery 22 so as to centralize the auxiliary wall 20 with respect to the outer shell 10, the periphery 22 cooperating with the inner wall of the outer shell 10 in defining spaces 23 between the lugs 21.

Suspended as by studs 24 from the auxiliary wall 20 is a sectional shell 25 of a drive means 26 which is preferably in the form of an electric motor including a stator 27 mounted in the shell 25 and a rotor 28 secured to a shaft 29. This shaft may be journaled by a bearing 30 mounted in a lower wall 31 of the shell 25 and by a bearing 32 mounted in the auxiliary wall 20, this shaft extending upward beyond the wall 25 as shown.

Resting on the spacers 19 is a wall 35 providing lugs similar to the lugs 21 so that the periphery of this wall is spaced from the outer shell 10, as best shown in Fig. 1. An inner shell 38 rests on the wall 35, being centralized with respect to the outer shell 10 by a ledge 39 formed on the wall 35. The upper end of the inner shell 38 is retained in position by a collar 40 which provides lugs 41 which centralize the collar 40 with respect to the outer shell 10 and which space the periphery of the collar from the outer shell to form passages 42, as shown, these lugs providing openings through which the rods 13 pass. The upper ends of the rods 13 are threaded so as to receive nuts 43 which may be threaded downward on these rods to engage the collar 40 and thus cooperate with the spacer means at the lower end of these rods in retaining the walls 20 and 35, as well as the inner shell 38, in fixed axial position, the nuts 43 being tightened prior to the time that the upper head 11 is secured in place.

The outer and inner shells 10 and 38 cooperate in defining an annular space 46, the upper end thereof communicating with the upper interior of the shell 10 and with the upper end of a piston chamber 48 defined inside the inner shell 38 above the wall 35, this communication taking place through a neck 49.

formed by an arcuate hood 50 of the collar 40. Slidably disposed in the piston chamber 48 is a piston 52 which moves in substantially fluid-tight relationship with the inner wall of the inner shell 38. A stop means 53 extends downward from the piston and is adapted to engage the ledge 39 of the wall 35 when the piston is in a lower position.

An operating rod 54 is secured to the piston 10 and extends upward through an opening 55 of the upper head 11, it being preferable to provide a seal 56 at this point. In the embodiment shown in Fig. 1, this seal comprises an annular flexible member 57 providing a lower portion 15 which engages a surface of the rod 54 in wiping relationship, this member being positioned in a cavity 58 and retained therein by a gland 59.

A spring 60 is preferably disposed around the rod 54 and resiliently supports a plate 61 which 20 engages an annular lip 62 of the head 11 prior to the time that the piston 52 engages the collar 40. The spring 60 thus acts as a resilient means for limiting the upward movement of the piston 52.

25 It is usually preferable to provide a resilient means for impeding the return movement of the piston 52. In the embodiment shown in Fig. 1 a spring 65 surrounds the rod 54 and rests on a boss 66 of the upper head 11. A 30 plate 67 is secured to the rod 54 in such a position as to come into engagement with the spring 65 just before the piston 52 reaches its lowermost position so that this spring acts as a resilient means for retarding the downward movement 35 of the piston 52.

It is usually desirable to protect the spring 65 and the seal 56 from dust and other foreign matter which might otherwise reach the interior of the shell 10. This is accomplished in the 40 preferred embodiment of the invention by means of a flexible member 70 secured to the plate 67 and the boss 66 and being expansible to compensate for the movement of the rod 54. In the preferred form of the invention this flexible 45 member is in the form of a piece of oiled duck creased to fold in the shape of a bellows, and it is usually desirable to interpose a spacing means 71 therein, this spacing means comprising a relatively weak spring disposed immediately 50 ly inside the flexible member 70 to hold this member in spaced relationship with the spring 65.

The interior of the outer shell 10 is filled to a 55 level *a—a* with oil or other operating liquid having relatively good dielectric properties so that opposite ends of the piston chamber 48 contain this operating liquid. The piston 52 is moved by hydraulic force set up when the operating liquid is pumped from the upper end 60 of the piston chamber 48 to the lower end thereof. This pumping action is effected by a pump means in the form of an impeller 75 connected to the motor shaft 29 and preferably disposed in the lower end of the piston chamber 48 so as to 65 intake through a port 76 formed centrally in the wall 35 and so as to discharge directly into the lower end of the piston chamber 48 in an outward direction.

70 Various types of pump means may be utilized, but in the preferred embodiment of the invention I prefer to utilize an impeller having an upper shroud 77 with vanes 78 depending downward therefrom, but being spaced a slight distance from the wall 35. The passage formed 75 between the vanes 78 of the impeller are always

in open communication with the port 76 and with the interior of the piston chamber so that when the motor 26 is de-energized the weight of the piston 52 and rod 54 returns the operating liquid, previously displaced, through the passages of the impeller in a reverse direction. It will be understood that the stop means 53 extends downward so as to engage the ledge 39 prior to the time that the piston 52 engages the impeller 75, thus preventing engagement between the piston and the impeller in the event that the spring 65 does not act to stop the return of the piston prior to the time the stop means 53 engages the ledge 39. When the motor 26 is again energized it will be clear that 10 operating liquid is drawn from the upper end of the piston chamber 48 through the annular space 46 and into an intake passage 79, disposed between the walls 20 and 35, and thence into the port 76 to the intake of the impeller, the 15 liquid being discharged under high pressure into the lower end of the piston chamber so as to exert an upward force on the piston 52.

20 It is preferable to utilize the pump means for a dual purpose, namely, to advance the piston 52 and to cool the motor 26 or other drive means. This is done by forming relatively small holes 80 through the lower wall 31 of the motor shell 25, and by providing ports 82 in the auxiliary wall 20 which communicate 25 with the interior of the motor shell and with the intake of the impeller 75. Thus, when this impeller is rotating it not only draws the operating liquid through the intake passage 79, but sets up a by-pass flow indicated by the arrows 35 84, this flow being downward around the outside of the motor shell and upward through the holes 80 and through the motor, this operating liquid then flowing through the ports 82 and into the impeller 75. This effectively cools the 40 motor at all times.

In addition, it is desirable that the circulation 45 through the motor 26 be maintained even though the piston 52 is in an advanced position. This is accomplished by providing relatively small openings 85 through the piston. Thus, even when the piston is in an advanced position a small flow of operating fluid takes place therethrough and moves downward through the annular space 46. A portion of this circulated liquid moves downward as indicated by the arrows 84 and through the motor in cooling 50 relationship therewith. The openings 85 serve another very useful purpose, namely, that of venting the space immediately below the piston 55 when the outer shell 10 is first filled with operating liquid. If these openings were not provided a body of gas would be entrapped immediately below the piston 52 when this operating liquid is poured into the shell.

The current to the motor may be supplied by any suitable means, but in the preferred embodiment the current is conducted through terminals 90 mounted in insulated relationship with respect to the upper head 11, as best shown 65 in Figs. 1 and 2. These terminals preferably extend below the level *a—a* and through a gas chamber 90a formed in the enclosing structure above this level so as to be connected to conductors 91 at a point below the surface of the 70 operating liquid, these conductors extending downward through the annular space 46 and into the motor 26.

The utilization of an impeller having but a single shroud is a very desirable feature, espe- 75

cially when such an impeller is positioned so as to discharge directly into the lower end of the piston chamber. From a manufacturing standpoint, the pressure developed by such an impeller can be readily varied either by changing the outer diameter of the impeller, or by changing the distance between the lower edges of the vanes 78 and the wall 35. This latter change also varies the amount of liquid pumped by the impeller and can be made either by turning down the vanes 78 or by changing the height of the spacers 19. It is further an important feature of the invention that the impeller discharge directly into one end of the piston chamber so that there is a minimum of turbulence as the operating fluid discharges. If the impeller discharges into curved passages, additional losses are set up.

The particular manner of structurally connecting the different elements is also an important feature of the invention. The apparatus can be readily adapted to different lengths of stroke by suitable design of the inner and outer shells without changing the design or size of the motor. Further, the type of motor mounting herein shown is of advantage in view of the fact that motors of different size may be utilized to control the rate at which the rod 54 is advanced.

Finally the structural connection between the elements is such that the parts are easily assembled with a minimum of bolts, and are rigidly held in place through the action of the rods 13 and the spacing means positioned thereon.

The complete structure may be mounted in any suitable manner as by a clevis 95 extending downward from the lower head 12, it being understood that the thrust is transmitted by the upper end of the rod 54 to any desired apparatus by any suitable connecting means.

I claim as my invention:

1. In combination in a self-contained thrust-producing device: a shell defining a piston chamber; a piston reciprocable in said piston chamber, said piston chamber being substantially filled on opposite sides of said piston with an operating liquid; pump means for transferring operating liquid from one end of said piston chamber to the other, to effect a movement of said piston; motor means positioned in said operating liquid and operatively connected to said pump means; and by-pass means communicating between the intake and discharge of said pump means and including a passage through said motor and through which by-pass means moves a portion of the operating liquid pumped by said pump means when said motor means is operating.

2. In combination in a self-contained thrust-producing device: an outer shell containing a body of operating liquid and including a piston chamber; a piston reciprocable in said piston chamber; an impeller means in said outer shell and spaced axially from said piston, said impeller providing intake means communicating with one side of said piston and discharge means communicating with the other side of said piston, whereby when said impeller means is rotated the liquid on one side of said piston is transferred to the other side of said piston to displace same, the displaced liquid returning through said impeller means when said impeller means is stationary; and an electric motor positioned in said liquid at one end of said piston

and operatively connected to said impeller means to rotate same.

3. In combination in a self-contained thrust-producing device: an outer shell containing an operating liquid; an inner shell mounted in said outer shell and defining a piston chamber, said inner shell being spaced from said outer shell to define an annular space communicating at one end with one end of said piston chamber; a piston reciprocable in said piston chamber, said piston chamber being filled on opposite sides of said piston with said operating liquid; a plunger operatively connected to said piston and extending from said outer shell; an impeller intake from one end of said piston chamber and discharging into the other end thereof whereby said piston is moved, the liquid pumped by said impeller passing through said annular space; and drive means for said impeller and including an electric motor mounted in said outer shell at one end of said inner shell and positioned directly beneath said inner shell in said operating liquid.

4. In combination in a self-contained thrust-producing device: an outer shell containing an operating liquid; an inner shell mounted in said outer shell and defining a piston chamber, said inner shell being spaced from said outer shell to define an annular space communicating at one end with one end of said piston chamber; a piston reciprocable in said piston chamber, said piston chamber being filled on opposite sides of said piston with said operating liquid; a plunger operatively connected to said piston and extending from said outer shell; a wall extending across said inner shell and providing a port communicating with said piston chamber; an impeller adjacent said port and moving said operating liquid therethrough; and drive means in the form of an electric motor below said wall and operatively connected to said impeller.

5. In combination in a self-contained thrust-producing device: an outer shell containing an operating liquid; an inner shell mounted in said outer shell and defining a piston chamber, said inner shell being spaced from said outer shell to define an annular space communicating at one end with one end of said piston chamber; a piston reciprocable in said piston chamber, said piston chamber being filled on opposite sides of said piston with said operating liquid; a plunger operatively connected to said piston and extending from said outer shell; a wall extending across said inner shell and providing a port communicating with said piston chamber; an auxiliary wall spaced from said wall and cooperating therewith to define a passage communicating with said annular space; an impeller adjacent said port and moving operating liquid from one end of said piston chamber to the other through said passage and said annular space; and electric motor means below said auxiliary wall and operatively connected to said impeller means.

6. In combination in a self-contained thrust-producing device: an outer shell containing an operating liquid; an inner shell mounted in said outer shell and defining a piston chamber, said inner shell being spaced from said outer shell to define an annular space communicating at one end with one end of said piston chamber; a piston reciprocable in said piston chamber, said piston chamber being filled on opposite sides of said piston with said operating liquid; a plunger operatively connected to said piston and extend-

ing from said outer shell; a wall extending across said inner shell and providing a port communicating with said piston chamber; an auxiliary wall spaced from said wall and co-operating therewith to define a passage communicating with said annular space; an impeller adjacent said port and moving operating liquid from one end of said piston chamber to the other through said passage and said annular space; an electric motor mounted below said auxiliary wall and in said operating liquid in said outer shell; and walls defining ports communicating with the interior of said electric motor and communicating with said impeller means whereby a flow of said operating liquid is set up through said electric motor.

7. In combination: a shell; a wall extending across one end of said shell and cooperating with said shell in defining a piston chamber; said wall providing a port communicating with said piston chamber; a piston reciprocable in said piston chamber, said piston chamber being substantially filled with an operating liquid on opposite sides of said piston; an impeller means 25 in said piston chamber and intaking from said port and discharging into one end of said piston chamber; and an electric motor on the opposite side of said wall from said impeller means for driving said impeller means to transfer the operating liquid from one side of said piston to the other to move said piston.

8. A combination as defined in claim 7 in which said impeller means comprises a shroud and vanes extending from said shroud and toward said wall, but terminating short thereof to define impeller passages opening directly on the interior of said piston chamber.

9. In combination: an outer shell; heads closing opposite ends of said outer shell; an inner shell in said outer shell and defining a piston chamber; a piston movable in said piston chamber, opposite ends of said piston chamber being filled with operating liquid; a wall extending across one end of said piston chamber; a rod connected to said piston and extending through one of said heads; a prime mover positioned between said wall and the other of said heads; and pump means driven by said prime mover for flowing said operating liquid from one end of said piston chamber to the other when said pump means is operating.

10. In combination: an outer shell; heads closing opposite ends of said outer shell; rods extending between said heads inside said outer shell to retain said heads in contact with said outer shell; an inner shell in said outer shell and defining a piston chamber; means including said rods for axially positioning said inner shell with respect to said outer shell; a piston movable in said piston chamber, opposite ends of said piston chamber being filled with an operating liquid; impeller means for moving operating liquid from one end of said piston chamber to the other to advance said piston; and drive means for said impeller means.

11. In combination: an outer shell; heads closing opposite ends of said outer shell; rods extending between said heads inside said outer shell; a wall inside said outer shell and through which said rods extend; an inner shell in said outer shell, one end of said inner shell abutting against said wall, said inner shell defining a piston chamber; a collar at the other end of said inner shell and through which said rods extend; means on said rods for spacing said

collar and said wall thereon in a manner to retain said inner shell therebetween; a piston movable in said piston chamber, opposite ends of said piston chamber being filled with an operating liquid; pump means for moving operating liquid from one end of said piston chamber to the other to advance said piston; and drive means for said pump means.

12. In combination: an outer shell; heads closing opposite ends of said outer shell; rods extending between said heads inside said outer shell; a wall inside said outer shell and through which said rods extend; an inner shell in said outer shell, one end of said inner shell abutting against said wall, said inner shell defining a piston chamber; a collar at the other end of said inner shell and through which said rods extend; motor means in said outer shell; mounting means for said motor means and through which said rods extend; spacer means adjacent said rods for spacing said mounting means, said wall, and said collar with respect to each other whereby said inner shell is clamped between said wall and said collar; a piston movable in said piston chamber, opposite ends of said piston chamber being filled with an operating liquid; and pump means driven by said motor means for moving operating liquid from one end of said piston chamber to the other to advance said piston.

13. In combination in a self-contained thrust-producing device: a shell containing a body of operating liquid and defining a piston chamber; an electric motor positioned in said shell directly beneath said chamber to be surrounded by said operating liquid in a manner to be cooled thereby; a piston in said chamber; pump means driven by said motor and intaking from one end of said piston chamber and discharging into the other end thereof to move said piston; and a plunger operated by said piston and extending through a wall of said shell.

14. In combination in a self-contained thrust-producing device: an outer shell; a plunger in the upper end of said outer shell and mounted to reciprocate therein; a rotatable shaft in the lower end of said outer shell and mounted to rotate about an axis common to the extended axis of said plunger; an electric motor for rotating said shaft and positioned in said lower end of said outer shell, said outer shell containing an operating liquid surrounding said electric motor; a piston on said plunger; and pump means driven by said shaft and positioned between said electric motor and said plunger for forcing a portion of said operating liquid into pressural contact with said piston to advance said plunger.

15. In combination in a self-contained thrust-producing device: walls forming a piston chamber, an intake passage, and a motor chamber substantially filled with an operating liquid and disposed in superposed relationship, said walls including a wall separating said piston chamber from said intake passage and providing a port; an impeller in said piston chamber and providing a central intake means opening directly on said port whereby operating liquid is drawn from said intake passage and through said port by said impeller and discharged into said piston chamber; a piston movable in said piston chamber under the action of said operating liquid reaching said piston chamber; a motor in said motor chamber and driving said impeller; and walls defining an opening in said walls form-

ing said motor chamber and communicating between said intake chamber and said motor chamber, said openings conducting operating liquid through said motor chamber under the influence of said impeller.

5 16. In combination in a self-contained thrust-producing device: an enclosing structure containing an operating liquid, the upper portion of said enclosing structure defining a gas chamber; walls forming a piston chamber in the upper portion of said enclosing structure; an electric motor in the lower portion of said enclosing structure below the surface of said operating liquid; a pump means driven by said electric motor and discharging into said piston chamber; a piston movable in said piston chamber; and conductor means extending through said enclosing structure and into said gas chamber and thence extending downward outside 10 said piston chamber to said electric motor for supplying current thereto.

15 17. In combination in a self-contained thrust-producing device; an outer shell containing a body of operating liquid; a head extending across one end of said outer shell and including an opening therein; a plunger extending through said opening; a piston movable upward and downward in said outer shell and secured to said plunger; a spring surrounding that portion of 20 said plunger extending beyond said head; means

associated with said plunger and engaging said spring when said piston nears its lowermost position to compress said spring; a pump means in said outer shell for forcing operating liquid into contact with said piston to advance said plunger; and a motor in said outer shell and operatively connected to said pump means.

18. In combination in a self-contained thrust-producing device: an outer shell containing a body of operating liquid; a head extending across one end of said outer shell and including an opening therein; a plunger extending through said opening; a piston movable upward and downward in said outer shell and secured to said plunger; a shoulder movable with said plunger and approaching said head when said plunger is moving downward; a compression spring around said plunger and compressed between said shoulder and said head when said plunger is close to its lowermost position to 25 cushion said piston and plunger; a flexible protecting member around said spring and secured at its one end to said head and at its other end to said plunger; a pump means in said outer shell for forcing operating liquid into contact with said piston to advance said plunger; and a motor in said outer shell and operatively connected to said pump means.

CARL E. JOHNSON. 30
